Primary Examiner — Catherine A Tuttle(74) Attorney, Agent, or Firm — Southeast IP Group LLC; Thomas L. Moses(57) CLAIM

The ornamental design for the flag puzzle, as shown and described.

DESCRIPTION

FIG. 1 is a top view of a flag puzzle showing my new design with its pieces in an assembled state;

FIG. 2 is a top view showing the design with its pieces in a separate state;

FIG. 3 is a bottom view of FIG. 1; and,

FIG. 4 is a bottom view of FIG. 2.

The black background is for the purpose of visibility of the puzzle and forms no part of the claimed design.

1 Claim, 4 Drawing Sheets(56)

1 Delaware	the first to ratify the Constitution, sent 4,000 troops to the war, won a battle at Queen's Bridge and prevented a British force landed to Philadelphia.	 George Washington First President of the United States
2 Pennsylvania	at Philadelphia on July 2, 1776 the Second Continental Congress sent King George the Declaration of Independence. He said, "Nothing important happened today".	 George Washington First President of the United States
3 New Jersey	taught the local bodies of the Revolution including General Washington's army the Constitution on Dec. 25, 1776 for a surprise attack on Trenton.	 George Washington First President of the United States
4 Georgia	signed the Declaration of Independence on July 4, 1776 while the war continued. Ethan Clarke, as a Lieutenant in the militia, led a charge in the victory at Kettle Creek.	 George Washington First President of the United States
5 Connecticut	handed the British with such "Tory" laws, raised Fort Ticonderoga and became the army supplier for the Revolution.	 George Washington First President of the United States
6 Massachusetts	started the revolution with protests, riots and men like Paul Revere, John Adams, Samuel Adams and John Hancock.	 George Washington First President of the United States
7 Maryland	General George Washington regarded "The Maryland Line" of the Continental Army as among his finest soldiers.	 George Washington First President of the United States
8 South Carolina	was a turning point in the war. It sent the British troops Bunker's suffering heavy casualties from Bunker's General Morgan.	 George Washington First President of the United States
9 New Hampshire	John Paul Jones' "Sons of Liberty" attacked Fort William and Mary, captured 18 cannons and the town of Portsmouth for Bunker Hill.	 George Washington First President of the United States
10 Virginia	the defeat of General Cornwallis by the allied forces at the Siege of Yorktown in 1781, brought the war to an end.	 George Washington First President of the United States
11 New York	British General Burgoyne's surrender of Saratoga was a turning point in the war because it connected the North and South Colonies.	 George Washington First President of the United States
12 North Carolina	raised with opposition from Tory troops, Cherokees and the British, protest troops destroyed a Loyalist force at Moore's Creek Bridge.	 George Washington First President of the United States
13 Rhode Island	troops sent the Hessian troops, "Grenadiers", marched in many skirmishes. These regulars raided the Continental Army and this began "The Rule of Law".	 George Washington First President of the United States

1 Delaware The First to ratify the Constitution, sent 4,998 troops to the west, won a battle at Cooey's Bridge, and entrenched a British Army in Boston.
2 Pennsylvania As Philadelphia is on July 2, 1776 the Second Continental Congress sent King George the Declaration of Independence. He said "Nothing important happened today".
3 New Jersey Received the secret Decrees of the Revolution including General Washington's ordering the Decree on Dec 26, 1776 for a surprise attack on Trenton.
4 Georgia signed the Declaration of Independence on July 4, 1776 while the war continued. Elijah Clarke, as a Lieutenant in the militia, led a charge in the victory at Kettle Creek.
5 Connecticut harnesses the English with steel, Troy brass, selected iron, McCormick and became the arms supplier for the Revolution.
6 Massachusetts Started the rebellion with protests, riots and men like Paul Revere, John Adams, Samuel Adams and John Hancock.
7 Maryland General George Washington suggested "This Maryland Line" of the Continental Army as among the finest soldiers.
8 South Carolina was a hunting ground in the west. It sent the British troops South supporting forces commanded from British General Morgan.
9 New Hampshire 's "sons of liberty" attacked Fort William and Mary, captured 1500 men and two tons of gunpowder for Bunker Hill.
10 Virginia The defeat of General Cornwallis by the allied forces at the Siege of Yorktown in 1781, brought the war to an end.
11 New York when General George's surrender of Saratoga was a turning point in the war because it connected the North and South Colonies.
12 North Carolina Faced with opposition from Tory Troops, Cherokee and the British, fought various battles in a long war in Monroe's Creek Valley.
13 Rhode Island became one the 1788 revenue enforcement, "Garrison" received in money campaigns. Their signature ratified the Constitution and this boggles "The Rule of Law".
